UNITED STATES PATENT OFFICE.

RUFUS L. PATTERSON, OF DURHAM, NORTH CAROLINA.

MACHINE FOR PACKING TOBACCO.

No. 829,288.

Specification of Letters Patent.

Patented Aug. 21, 1906.

Application filed August 20, 1897. Serial No. 648,936.

To all whom it may concern:

Be it known that I, RUFUS L. PATTERSON, a citizen of the United States, residing at Durham, in the county of Durham and State 5 of North Carolina, have invented certain new and useful Improvements in Machines for Packing Tobacco and other Merchandise, of which the following is a specification.

My invention pertains to machinery for 10 packing tobacco and other merchandise. In its most complete form the machine is adapted to measure the substance to be packed, to weigh it with great accuracy, to place it in bags or other holders and compress it there- 15 in, to apply a revenue-stamp to the package, to apply one or more labels, and, if desired, introduce a package of cigarette-papers, a card, or other token beneath one of the labels, and finally to deliver the finished packages 20 in regular order to a tray or receptacle.

The present invention is in the nature of an improvement upon that set forth in Letters Patent No. 579,546, granted to me on the 23d day of March, 1897. Portions of the 25 mechanism may be operated without of necessity using others, and this may be done either by throwing out of action those parts not required or by embodying in the structure only such parts as are needed for the 30 special work in hand.

The accompanying drawings illustrate my improved machine in its complete form and as specially fitted for filling, stamping, and labeling tobacco bags or packages, it being 35 deemed desirable and important to show and describe in one application the entire or complete mechanism for handling the tobacco from the time that it comes from the granulator to the time that the packages are ar- 40 ranged in order for delivery to the packing tables or boxes.

In applications, Serial Nos. 82,906 and 45 82,907, filed in the Patent Office on the 19th day of November, 1901, as divisions of this application, and pursuant to requirements of the Patent Office, I have shown, described, and claimed in the first the stamping and labeling mechanism and in the second the measuring and weighing mechanism herein 50 shown and described. Said applications have resulted in patents, application Serial No. 82,906 becoming Patent No. 765,147, of July 12, 1904, and application Serial No. 82,907 becoming Patent No. 754,937, of 55 March 15, 1904. The retention of a general description and illustration of these matters

in the present application is for the purpose of more perfectly and completely illustrating and describing the invention here involved and to show in one application the complete 60 and organized machine.

Figure 1 is a perspective view of the entire machine, designed to give an idea of its general appearance. Fig. 2 is a side elevation of the measuring, weighing, filling, and packing 65 mechanisms; Fig. 3, a sectional elevation showing the cam and lever mechanism by which the presser-head and package-ejector are actuated; Fig. 4, a perspective view of one of the forms or holders in which the bag 70 or package is held and carried while being filled, pressed, &c.; Fig. 5, a sectional view showing the retaining-guides for accurately locating and holding the form during compression of the charge; Fig. 6, a top plan view 75 of the bed or table of the machine, with the measuring and weighing devices removed and the mechanism beneath the table indicated by dotted lines; Fig. 7, a top plan view of the cam and lever mechanism for actuating the measuring devices and for dumping the scale-pans; Fig. 8, a top plan view of the rotary shape-carrier and bag-shapes; Fig. 9, a front or end elevation of the measuring, 80 weighing, and pressing mechanisms looking 85 from the delivery end of the machine, the stamping and labeling mechanism being omitted; Fig. 10, a sectional view showing the manner of mounting and actuating the shape-carrier and locking it against accidental movement; Fig. 11, a bottom plan view 90 of said actuating and locking devices; Fig. 12, a top plan view of the mechanism between the packing mechanism and the receiving-tray, by and through which intermediate 95 mechanism the bag or package is transferred from the one to the other; Fig. 13, an end elevation of the same; Figs. 14, 15, and 16, detail views of the mechanism by which the package is delivered from the way or track which 100 receives it as it comes from the packing mechanism to a lower way or track by which it passes to the tray; Figs. 17 and 18, end elevations showing the mechanism by which the packages are carried toward the tray; Fig. 19, 105 a similar view showing the receiving and delivery wheel and the tray; Fig. 20, a detail thereof.

General Outline of Machine.

It will conduce to clearness and facility of understanding to briefly describe the ma-

chine as a whole and thereafter to explain its various groups of mechanism in detail, taking them in the order in which the tobacco or other merchandise reaches and is acted upon by each. In the handling of tobacco and, in fact, with many other kinds of merchandise it is found expedient to place the stock of material on an upper floor and the packing and labeling mechanism on a lower floor, suitable spouts or chutes leading from the bin or stock-hopper to the measuring mechanism. The present machine employs for measuring a wheel or wheels with buckets or compartments of predetermined size and mechanism for moving said wheels so as to employ one or more than one of the compartments at each operation, according to the intended size of the package. The extent of movement of the measuring wheel or wheels at each step is determined by varying the point of connection between the pawl-carrying lever through which the necessary rotation is effected and an actuating-lever of uniform throw. From the measuring-wheel the charge is delivered into a scale-pan, into which is gradually delivered such additional quantity as shall bring the charge to the precise weight required, essentially as in my former patent, dated March 23, 1897, and numbered 30 579,546, the dumping of the scale-pan being likewise automatically and positively effected in a manner similar to that of the previous machine. The scale-pan or the several pans, if there be more than one, will deliver into a single hopper, as before, by which each charge in turn will be directed into a "bag-shape," carried by a horizontally-rotatable shape-carrier, which periodically rises to permit the application of a bag to one shape, to 40 carry the preceding bag up to the delivery end of the hopper, to carry a filled bag to the bag form and presser, and to move another shape to a point where a lever or other device is arranged to act upon and collapse it preparatory to the application of another bag. In the present machine the "bag-forms" are carried by or form parts of an endless chain which travels over a horizontal bed or table, thence downward, backward beneath the table, and finally upward again to the top of the bed or table. This chain is advanced 50 step by step with sufficient delay or "dwell" between steps to afford time for the several operations noted and also sufficient to permit the tobacco or other substance to become "set" in shape. Without an appreciable dwell of the package while in the form and subject to pressure there is a liability of its rising as soon as the pressure is removed, and thereby impairing the symmetry of the package and causing a slight variation in size. In that portion of travel of the chain during which the forms descend from the table the packages are (or may be) tied by hand or

are otherwise closed, after which they are 65 forced out of the forms one after another.

When the stamping or stamping and labeling appliances are used, the ejector is so arranged as to deliver the package directly against a vertically-disposed stamp, previously gummed or pasted, the package being thrust between rollers or folders which cause the stamp to be duly bent or folded about the package. After being thus stamped the package is moved along a horizontal track or 75 way, through which it is lowered against a "district" or "caution" label, which is folded about the package by suitable devices, a card, cigarette-paper package, or the like being first applied so as to be bound by this 80 label, if desired. The packages are next moved sidewise beneath a paste-roller, then beneath a label-holder, which descends and leaves a label lightly attached to the face of the package, and thereafter passes beneath a 85 presser, which causes perfect contact of the label throughout its area and insures thorough adhesion. Lastly, the packages are delivered one after another between the blades of a rotating wheel or carrier, which deposits 90 them in a tray, wherein they are shoved transversely until a line is formed from side to side, whereupon the entire line is advanced toward the lower end of the tray to make room for a second line, this action being repeated until the tray is filled, removed, and replaced by an empty one.

Having now outlined the general plan of construction and operation, I will describe in detail the various parts, beginning with the 100

Feed-Hoppers.

In practice it is found expedient and, in fact, almost essential to employ a plurality of measuring and weighing devices operating 105 successively or in alternation in order that each may work slowly enough to insure perfect action, yet there shall be such frequent delivery of charges as shall enable the packing and labeling mechanism to run rapidly, 110 thus securing high efficiency both as to quantity and as to quality of work. In the present instance I have represented four measuring and weighing mechanisms, each of which advisably receives its supply from 115 an independent hopper of special construction and arrangement, which, however, is not here set forth in detail, but is claimed in Patent No. 754,937, issued upon application Serial No. 82,907, above referred to. Each hopper 120 delivers into a spout or trunk 7, extending from the delivery end or mouth of the hopper to the shell or casing 8 of one or another of the measuring-wheels. From each shell or casing 8 the tobacco or other merchandise passes 125 to a scale-pan 42, carried by a scale-beam 41 and located above or partly within a hopper 59, common to the series of scale-pans. The

filling of each scale-pan, which is very accurately performed by special contrivances carried into a divisional application, causes it to descend and in descending to open and discharge its contents into and through a common hopper or funnel 59, carried by an arm 60, projecting from the column 10, as seen in Fig. 2, and thence into the funnels or hopper-shaped mouths of bag-shapes 66. Column 10 rises from a bed or table 61, supported by the main frame 62 of the machine.

Shape-Carrier.

Rising from the bed or table 61 is a hollow post or column 63, in which is mounted a vertical shaft or spindle 64, capable both of a rising and falling motion and of rotation about its axis. Mounted upon the upper end of this spindle is a four-armed head 65, the arms being arranged at right angles to one another or ninety degrees apart. Each arm carries a bag-shape 66, having a hinged side portion 67 at the lower end, designed to be swung inward to permit a bag to be readily slipped upon it, after which, by pressure upon the hinged side above its pivot, it may be restored to position, and thus caused to stretch and hold the bag thereon. The manner of mounting and operating the spindle 30 and its shape-carrier is illustrated in Figs. 2, 10, and 11. Referring first to Fig. 10, it will be seen that the spindle is centrally bored at its lower end to receive the stem of an eye-block 68, which block is connected with a vertically-movable lever 69 by a pin 70, passing through the slotted end of the lever and through the eye-block, as seen in Fig. 2. A pin 71, passing through a hole in spindle 64 and fitting a groove in the stem of eye-block 40 68, connects said parts, yet permits free rotation of the spindle independently of the block.

Encircling the spindle 64 is a sleeve 72, which extends upward through an opening in the bed or table 61 and is maintained at proper elevation by a series of antifriction-rollers 73, carried by adjustable blocks 74 and extending into a circumferential groove in the upper part of the sleeve, as seen in Fig. 10. The blocks 74 are slotted and are clamped and held at any desired adjustment upon the bed or table 61 by tap-bolts 75. Beneath the table 61 the sleeve 72 is formed or furnished with a disk 76, in the periphery 55 of which are formed four notches 77, designed to receive successively a locking-bolt 78, by which the spindle and its shape-carrying head are held accurately in proper position during operation of other parts. Formed 60 with or secured to disk 76 is a second disk 79, having four radial shoulders or faces 80, connected by long curves or inclines, as seen in Fig. 11, thus making a ratchet-disk. Below the ratchet-disk 79 is a pawl-carrier 81, made 65 in the form of a circular plate encircling the

lower or depending portion of sleeve 72 and provided with an outwardly-extending arm to which is applied a pawl 82, which engages with the teeth or faces 80 of disk 79 successively. The pawl-carrier 81 is oscillated about the axis of spindle 64 by a vibrating lever 83 through the medium of a connecting-rod 84, the lever being shown in Fig. 2 actuated by a cam 112.

The locking-bolt 78 is pressed forward by 75 a spring 85, encircling the bolt, both being contained within a shell or casing 86, which contains also an annular follower 87, which can be set forward as required by a screw 88 to vary the compression and consequent 80 pressure of the spring. The purpose of the locking-bolt is to arrest the rotation of the shape-carrier and to hold it in the precise position required while one bag is being applied, another is being filled, another is being 85 packed or compressed, and a fourth is being removed. It is of course necessary to withdraw or to force back the locking-bolt when the shape-carrier is to be advanced, and to accomplish this I provide the pawl-carrier 81 90 with a cam 89 to act against a roller 90, carried by a slide or bar 91, connected with bolt 78, as shown in Fig. 10. As the pawl-carrier 81 moves backward to engage a new tooth or shoulder 80 of the ratchet-disk 79 cam 89 95 forces back the roller 90, and with it the slide 91 and locking-bolt 78, thus releasing disk 76. As the pawl-carrier again moves forward its pawl advances the disk 79, and with it the released disk 76, the cam 89 gradually riding out from in front of roller 90 and leaving the slide 91 and locking-bolt 78 free to advance, and thus enabling the nose of the bolt to enter one of the notches 77 as soon as said notch comes into position to receive it. 100

The entire weight of the shape-carrier is borne by eye-block 68 and lever 69, so that the rollers 73 have only to support the weight of sleeve 72, its disks, and the pawl-carrier 81, which latter is retained in place 110 upon the sleeve by a nut or collar 92. A spline or feather 93 so connects the spindle 64 and sleeve 72 that they are compelled to rotate in unison, though the spindle is free to rise and fall through and independently of 115 the sleeve.

Referring now to Figs. 2 and 6, it will be seen that a main driving-shaft 35 is carried in boxes or bearings at the end of the main frame 62, said shaft being furnished with a 120 band-wheel 94, adapted to be clutched to or unclutched from a beveled or conical disk 95, made fast to the shaft. The details of this clutch form no part of this invention, hence need not be described, though it may 125 be mentioned that a lever 96 connects by a rod 97 with the sleeve 98, by which the band-wheel is pressed into working contact with disk 95.

Keyed or otherwise made fast upon shaft 130

35 is a pinion 99, which meshes with a gear-wheel 100, carried by a shaft 101, mounted in boxes or bearings in the main frame 62. At one end shaft 101 carries a bevel-pinion 102, which meshing with a like pinion 103 gives rotation to a shaft 104, through which the stamping and labeling mechanism is operated. At its other end shaft 101 carries a bevel-pinion 105, which meshes with a bevel-gear 106, carried at the lower end of a shaft 107, the upper end of which carries a bevel-pinion 108, which, as seen in Fig. 2, meshes with a bevel-pinion 109 on shaft 29, thereby rotating said shaft and giving motion to the measuring-wheels and pan-emptying devices through the cam and lever mechanism already mentioned. As seen in Fig. 2, shaft 101 also carries a cam 110, which acting beneath a stud or roller 111, projecting from the side of lever 69, serves to raise and lower said lever, and with it the shape-carrier, the lever being conveniently fulcrumed on shaft 35. Also carried by shaft 101 is a cam 112, grooved in the side face to receive the stud or roller 113 of lever 83, which actuates the pawl-carrier 81, by which the shape-carrier is rotated.

As shown in Figs. 1 and 6, there is located at the forward side of the machine a seat 114 for an attendant and directly in front of him a table or tray with raised sides, the tray being designed to hold bags or pouches. The operator or attendant sitting upon the seat 114 slips a bag or pouch upon the collapsed lower end of the bag-shape 66 in front of him, taking care to push it well up thereon, and as soon as this is done he presses the hinged side 67 at a point above its pivot, thereby spreading the lower end of the shape and stretching the bag or pouch, which is at the same time straightened thereon. A little practice enables an ordinary factory hand to do this work deftly and accurately. While the bag or pouch is being applied and the shape-carrier is in its elevated position, the bag previously applied to the next shape in advance receives its charge through the funnel 59 from one of the scale-pans 42. At the next turn or step of the shape-carrier the charged bag or pouch is carried over a bag form or receiver 115 and beneath a presser-head 116, (seen in Figs. 1, 3, 5, and 9,) the carrier then descending to cause the charged bag or pouch to enter the form or receiver.

55

Bag-Forms.

The bag-forms are shown in Figs. 1 to 5, inclusive, and consist each of a rectangular bottomless box 115. A series of these forms is used connected one with another by links 118, whereby there is formed an endless chain, as best seen in Figs. 2 and 3. This chain travels over the bed or table 61, with the lower ends of the boxes or forms in contact with or in close proximity to its surface.

As seen in Fig. 4, each box or form 115 is provided with lugs or ears 119 to receive the pins or rods 120, by which the links 118 are connected with the forms. If desired, the ends of these pins or rods may be allowed to project beyond the end walls of the forms to serve as axles for antifriction-rolls 121. These rolls may be arranged to project slightly below the ends of the forms, so as to travel upon the surface of bed or table 61, though this is not important, their principal purpose being to insure easy engagement with and disengagement from a notched driving wheel or sprocket 122, Figs. 2 and 3. The form-chain passes about four wheels or drums, one, 123, located at the edge or end of table 61, another, 124, located about midway between the ends of said table in the opening therein, a third, 125, carried in an adjustable yoke 126 directly below the wheel or drum 123, and the fourth being the sprocket-wheel 122, located directly beneath wheel 123 and at the same horizontal level as wheel or drum 125. The chain thus produces a parallelogram one side of which lies along the top of bed or table 61, which forms a support for that stretch of the chain and for its boxes or forms 115. At the point where the form-chain rises through table 61, which is near its mid-length, a curved guard or shield 127 is arranged to prevent the chain from encountering anything placed or falling upon the table. The chain, with its form-boxes, is required to advance step by step, and in doing so to bring one bag-form directly beneath a bag-shape 66 of the carrier-head 65 and another in line with an ejector hereinafter described.

To effect the proper advance and positioning of the boxes or forms, sprocket-wheel 122 or its shaft 128 is furnished with a ratchet-wheel 129, and there is loosely hung upon the shaft 128 a lever or pawl-carrier 130, provided with a pawl or dog 131, which as the pawl-carrier oscillates about the shaft alternately rides back over, engages, and presses forward against the teeth of the ratchet-wheel 129. Pawl-carrier 130 is actuated by a rod 132, provided with a yoke 133, which encompasses and is guided upon the hub or boss of a cam 134, which cam acting between and against two studs or rollers 135 and 136 on the yoke imparts longitudinal motion thereto and to rod 132. The outline of the cam is such that during considerable portions of its revolution it holds the yoke and rod at rest, these periods being accurately timed to agree with the periods of charging the bags, compressing, and ejecting the package. Cam 134 is carried by shaft 101.

It is important that the forms come accurately beneath the presser-head 116 and that they be held against lifting up with the shapes or the presser-head. Each form is therefore provided with two horizontal ribs

137, which pass beneath overhanging flanges of fixed bars 138, secured to bed 61, the lower ends of the forms passing between guide ribs or rails 139 on the bed, which serve 5 also as tracks for the rollers 121, as will be seen upon referring to Fig. 5.

Shape-Collapser.

It has been mentioned that the bag-shapes 10 66 have a hinged or pivoted wall 67, which may be thrown inward at the lower end to facilitate application of the bag. For the purpose of thus reducing or collapsing the shape I provide a bunter 140, Figs. 2 and 6, pin-15 jointed to a horizontal stem 141, guided in a block on the bed or table 61 and periodically pressed forward by a lever 142, connected by a link 143 with a second lever 144, fulcrumed in the main frame 62. The lower end of lever 144 stands in the path of an arm 145, carried by rod 132, as seen in Figs. 2 and 9, and is actuated by said arm as pawl-carrier 130 swings forward to carry pawl 131 into engagement with a fresh tooth of ratchet-wheel 129 and at a time when the carrier-head 65 and the bag-shapes are lowered and at rest.

Pressing Mechanism.

30 A charge of tobacco (or other merchandise) having been delivered into a bag carried by one of the bag-shapes 66 and this shape having been carried to a position directly beneath the presser-head 116 and lowered into 35 one of the forms 115, the head is caused to descend into the shape, and thus into the bag encompassing the lower end thereof, giving the necessary pressure to render the package solid and compact and continuing that pressure 40 a sufficient length of time to cause the contents to become set. After the head has descended and applied the pressure the shape-carrier is elevated, leaving the bag within the form 115 and the head 116 still 45 pressing upon its contents. A proper period of rest having been afforded during which the particles arrange themselves and the package acquires a permanent shape the head 116 rises, leaving the bag and its contents 50 in the form 115, which then advances to a point where the closing-string is tied or the pouch is otherwise closed.

The several movements of the shape-carrier are effected by mechanism already described, and the movements of head 116 are produced by mechanism shown in Figs. 2 and 3. As best shown in the latter figure, the rod or stem 146 of the presser-head 116 is carried by a sliding block or cross-head 147, 55 guided in an upright column or standard 148, rising from the bed or table 61. The cross head or slide 147 is connected by a pitman 149 with the free end of a lever 150, fulcrumed on the shaft 35 and periodically 60 raised and lowered by cam-plates 151 and

152, secured to or formed upon one face of the large gear-wheel 100, carried by shaft 101. The outlines of these cam-plates and their location upon the gear may be so varied as to give any desired range and time of 70 movement and period of rest. In practice they are so formed and arranged as to draw down the head 116 just after the bag is lowered into the form, and to hold it down during the subsequent rise of the shape-carrier 75 the filling of a fresh bag or pouch and until it again becomes necessary to rotate or advance the shape-carrier one step. It will be observed that the lever 150 is furnished with a stud 153, which enters the groove or space 80 between the cam-plates 151 and 152, and that this stud is located directly over the shaft 101, so that as the lever 150 is lowered the stud 153 comes nearer the axis of the shaft, and the movement of the lever, and 85 consequently of presser-head 116, becomes slower and the force or pressure becomes greater, thus giving the peculiar action so important in pressing.

Tag-Guide.

90

The package having been duly compressed and carried forward by the form-carrier and the string having been tied or the end otherwise closed, the package passes to an ejector. 95 In some factories it is customary to apply to the bag a printed tag of strong paper or other suitable material and a package or book of cigarette-papers. These, attached by a string and free to swing about, are liable 100 to catch into or to be caught by the mechanism, and thus to cause injury to the package or injury or stoppage of the machine. To prevent this, there is provided a guide 154, (seen in Fig. 2,) which, however, is carried 105 into a divisional application and need not be here described in detail.

The Ejector.

It has been stated that the bags or packages after being duly closed are ejected from the form-carriers in the descending stretch or section of the form-chain. The mechanism by which this is done is shown in Fig. 3. The ejector consists simply of a horizontal rod or 110 bar 163, the forward end of which is carried through a guide attached to the frame 62 and the other end of which is made fast to a block 164, fitting upon and guided by a horizontal bar 165. Block 164 is connected by a 115 link 166 or in any equivalent way with a lever 167, fulcrumed at its lower end in or upon a part of the machine-frame. Lever 167 is in turn connected by a link 168 with a lever 169, fulcrumed at its upper end in main 120 frame 62 and provided with a stud or roller 170, which is acted upon by a cam 171, carried by shaft 101. This may be a covered cam, in which case it will serve to positively 125 withdraw or recede the ejector, as well as to 130

move it outward, or it may be merely an open cam, in which case a spring or equivalent means will be provided to recede or return the ejector. Arms 176, having overhanging flanges, engage over the ribs 137 of the form-boxes as one after another they come opposite the ejector. These arms prevent the form from moving while the ejector is acting. All the parts thus far described are timed to operate in proper order or sequence; but to guard against the form-chain being carried by momentum a greater distance at one throw of its actuating-pawl than is desirable shaft 128, Figs. 6 and 9, which carries sprocket-wheel 122, is provided with a stop-wheel 172, having notches in its periphery corresponding in number and arrangement with the teeth of ratchet-wheel 129. A spring-pressed locking-bolt 173 is arranged to engage in the notches of wheel 172 as they are successively brought into line therewith, and thus to hold the shaft 128 and the sprocket-wheel 122 against movement until the bolt is withdrawn. This occurs once in each revolution of shaft 101 or once in each revolution of shaft 104 by reason of a cam wheel or disk 174, carried by shaft 104, acting against a lateral arm 175 of the bolt, advisably furnished with an antifriction-roller, Fig. 6. Directly in front of that part of the form-chain which passes vertically downward at the end of table 61 there is arranged a seat 177 for the attendant, by whom the bag-strings are tied if this mode of closure be adopted, as is commonly done in packing tobacco. This seat is seen in Fig. 13 supported by an arched cross-bar 178, extending from side to side of frame 62. It is omitted from other figures to permit other parts to be more clearly shown. Foot-rests 179 (seen in Figs. 6 and 9) are provided to give a proper support for the feet of the attendant and to prevent interference with or injury by moving parts of the machine.

45 Package-Transferring Mechanism.

As above indicated, the complete machine is designed to apply to the packages revenue-stamps and certain labels and finally to deliver them into a tray for package and shipment. So much of said mechanism as is necessary to the transference of the package from the packing mechanism to the tray will now be described, other matters being omitted because carried into a separate and divisional application.

The ejector 163 forces the package from the form 115 to or upon a track or way 158, (seen in top plan view in Fig. 12 and in end elevation in Figs. 13, 14, and 15, Figs. 14 and 15 showing that portion or section of the track 158 which has hinged or yielding bottom plates or flanges to permit the package to be forced downward through the track to a support beneath.) In passing over the

track or way 158 to the yielding supports 211 the package receives a revenue-stamp, a label, or the like. The ejector delivers the package to the track or way 158 and may itself carry it along the same to the point at which the yielding plates or supports 211 are located, or its travel to aid supports may be completed through the pressure of a succeeding package. Arriving at said point the package is forced down through the track by a vertically-movable head or plunger 212, suspended by a link or bar 213 from the free end of a lever 214, fulcrumed on the main frame of the machine, and moved at proper times by a cam 224 on the shaft 223, acting upon a stud or bowl carried by said lever 214. Directly beneath the yielding portion of the track 158, which is preferably spring-sustained, but may be counterweighted, is a block or carrier 215, which receives the package as it is forced down and at proper time drops with it to the level of supporting plate or way 270 and between guides or guards 264. (See Figs. 12 and 17.) In being lowered from the one track or way to the other the package receives a second paper strip or label, in the present instance the so-called "caution-label" required on tobacco-packages.

A horizontally-swinging lever 271, swinging about a vertical axis and moved in one direction by a cam 272 and in the opposite direction by a spring or equivalent means, moves the package along the supporting way or plate 270 to a point in line with a third bed or way 273, which stands at right angles to the plate 270. The bed or way 273 is provided with raised edges or guides to insure the retention and proper travel of the packages, which are advanced by mechanism illustrated in Figs. 12, 17, and 18. As shown in these figures, a horizontal bar 274 is suitably supported in the main frame of the machine and serves to sustain and guide a slide 275, which is connected by a link 276 with the upper end of a lever 277, fulcrumed at its lower end in a suitable bracket or support and connected at an intermediate point with a link 278, connected with an elbow-lever 279, acted upon by a cam 280. The lever 279 is advisably furnished with a roller for the cam to act against to move it in one direction, and a long and highly-elastic spiral spring 281 serves to move the lever and the connected parts in the reverse direction to that in which they are moved by cam 280.

Projecting horizontally from the side of slide 275 is an arm 282, Fig. 12, which extends nearly or quite across the bed or way 273 and is at proper height to engage and move a bag or package lying thereon. It will thus be seen that as the packages are carried by sweep 271 to the end of way 264, one after another, the arm 282 will carry them sidewise or at right angles to their previous travel and deliver them from the way

264 to the way 273, over which are located devices for delivering paste to the packages, applying a face-label thereto, and pressing said label firmly thereon until it becomes 5 smoothly and perfectly set and secured. These devices need not be specifically described, as they do not enter into the claims of the present application. As the packages arrive one after another upon the way 264 10 and are moved forward by the arm 282 they are moved over and off the way or platform 273 to a delivery-wheel, which in turn delivers them into a tray.

Delivery Mechanism.

15 The delivery mechanism is illustrated in Figs. 1 and 19 and will now be explained. At the side of the main frame 62 and in line with the way or table 273 there is located a 20 wheel or drum 326, provided with outwardly-projecting blades or wings 327, arranged in pairs, the blades of each pair being parallel to each other and to a line radial to the axis of the drum or wheel. The blades are of a 25 length in the direction of the axis of the wheel about equal to the length of the bag or package and project a distance about equal to the width thereof, while the space between them is sufficiently greater than the 30 thickness of the packages to permit the latter to enter and leave the spaces freely. The position of the wheel or carrier is such that the parallel blades or wings 327, which for the time occupy a horizontal position at the 35 side toward the way or table 273, shall be in proper position to receive between them the package pushed from the outer end of said way, the lower blade of the pair forming a continuation of said way, as seen in Fig. 19. 40 The wheel 326 is furnished with a ratchet-wheel 328, having a number of teeth equal to the number of pockets or receiving-spaces between the pairs of blades or wings 327, and a step-by-step rotation is imparted to the 45 ratchet-wheel, and consequently to the carrier-wheel, by a pawl or dog 329, carried by an arm or lever 330, loosely hung upon the axle of said drum or upon the bracket-arm 331, by which said axle is supported, as seen 50 in Fig. 21. A to-and-fro motion is imparted to pawl carrier or lever 330 by a rod 332, one end of which is connected with the lower end of elbow-lever 279, through which motion is 55 imparted to slide 275. (See Fig. 19.) The ratchet and pawl are so formed and set that during the forward or outward movement of slide 275, during which the package is carried into the carrier-wheel, said wheel remains at rest and the pawl simply rides back over 60 the ratchet-wheel to engage a fresh tooth, the carrier-wheel being turned during the rearward movement of slide 275. Carrier-wheel 326 advances the packages by a series of steps over its upper side and downward to 65 a point directly beneath its axis, a guard 333

being provided for the lower side of the carrier to prevent the packages from falling out prematurely. Upon reaching the lower side of the carrier-wheel and clearing the guard 333 the packages drop down and rest upon 70 their edges or narrower sides upon a board or way 334, provided with guide-walls 335, between which the packages are moved lengthwise, one after another, to a point beyond the outer wall 335 and in line with an ejector 75 336, by which they are shoved facewise into the tray 337.

The longitudinal movement of the packages between the walls 335 is effected by a 80 rod 338, Figs. 20 and 21, carried by an arm 339, clamped by set-screw or equivalent means upon rod 316, which actuates elbow-lever 315 and through it the rock-shaft 312. By adjusting the rod in its arm 339 or adjusting said arm upon rod 316 the limit of 85 travel of the rod, and consequently the point at which the packages shall be delivered, may be nicely determined. The package having been delivered by the rod 338 to a point in front of ejector 336, rods 338 and 340 withdraw by reason of the backward movement 90 of rod 316, elbow-lever 315 being at the same time swung backward and connecting-rod 314 drawn down. Rod 314 carries an adjustable sleeve 345, provided with a lateral 95 stud or finger 346, (seen in Figs. 19 and 21,) which stud engages a bent lever 347, causing its lower end to swing outward and to give longitudinal motion to ejector 336, with which it is connected by a link 348. The return movement of the lever 347 and ejector 336 may be effected by a spring or equivalent means.

Receiving-Tray.

105 In tobacco-factories it is customary to place the finished packages in trays of given dimensions and capable of containing an ascertained number of packages, and this is still desirable as a matter of convenience in 110 counting and handling, though it is found that by the selection of a suitable paste and the use thereof in small and uniform quantity the necessity heretofore existing of drying the packages is obviated. This, though 115 an incident to the use of the machine, is a matter of very considerable saving in time, labor, and space required.

In Fig. 1 I have shown the preferred form of tray, with mechanism for effecting the advance of the rows of packages as one row after another is completed. Referring to Fig. 1, the tray 337 will be seen to consist merely of a rectangular bottom-board with raised sides, being essentially the tray in general 120 use. Within the tray is placed a temporary tray or delivery-board 349, having raised sides and preferably a corrugated bottom. The lower end of the delivery-board 349 rests upon the bottom of the tray 337, at the 125 130

lower end of the latter, while the upper end of the delivery-board rests upon the raised end wall of tray 337, as shown. At the head of the delivery-board 349 is a board or bunter 350, connected by a rod 351 to one end of a lever 352, the other end of which is periodically engaged by a stud 353 on an endless chain 354, carried about two sprocket-wheels 355 and 356, the lever being retracted by a spring 357. Sprocket-wheel 356 is carried by a shaft 358, connected by a knuckle or universal joint 359 with shaft 107, as seen in Fig. 1, shaft 358 being omitted from the other figures to avoid obscuring parts beyond. The board or bunter 350 advances at stated intervals and moves sidewise the entire line or row of packages extending across the tray, moving them one bag length or a little more to make room for the next row. This action is repeated until the delivery-board or temporary tray 349 is filled, whereupon the attendant, making use of a rake or scraper 360, (seen in Fig. 1,) draws all the packages from the delivery-board or temporary tray 349 into the tray 337, which is simultaneously drawn lengthwise from beneath the delivery-board. An empty tray 337 is then substituted for the one removed and the work is repeated. The rake or scraper is separately shown to the right of the tray in Fig. 1 and on smaller scale for want of space. It is of the same length as the tray or a little more and has at the end of the handle or staff a downwardly-bent end or hook, which after the blade or head is dropped back of the rear or uppermost row of packages is dropped over and caused to engage with the lower end of the removable or bottom tray, so that in the act of withdrawing said tray from beneath the delivery-board or temporary tray 349 the rake 360 draws off the packages into the permanent tray 337.

45 Shape-Carrier.

By referring to Figs. 1, 2, 8, and 9 it will be seen that the shape carrier or head is formed with four bifurcated arms and that each bag-shape, or the funnel top thereof, is formed with lateral ribs or flanges 377 to rest upon the branches of said arms, where they are held by swinging latches or retaining-bars 378, hinged at one end to the arms and arranged to swing horizontally to and from a position over the ribs or flanges 377. This construction permits ready application and removal of the shapes, which provision is desirable, since by such change and by proper adjustment of the measuring and weighing devices, the forms, and certain other parts the machine may be readily adapted to prepare packages of different sizes.

The shape-carrier is guided in its vertical movements by an upright stem or post 379,

Figs. 8 and 9, each arm of the carrier being 65 perforated to receive said post in turn, essentially as in the former machine.

Numerous variations are permissible within the scope and spirit of my invention.

I claim—

1. In combination with a bed or table, a circumferentially-grooved sleeve; a series of rollers supported by said bed or table and extending into the circumferential groove of the sleeve; means for rotating the sleeve; 75 and a rod or stem longitudinally movable through the sleeve but held against rotation therein substantially as set forth, whereby the sleeve is held in position and is enabled to turn freely.

2. In combination with a bed or table and with a tubular post or standard thereon, a vertically-reciprocating stem or spindle 64 provided with a shape-carrying head 65; eye-block 68 swiveled in the lower end of 85 said spindle; lever 69 connected with the eye-block and serving to raise and lower the spindle; a sleeve 72 encircling the spindle and splined thereto; a circumferential groove formed in said sleeve; rollers 73 extending 9c into said groove and supported by the bed or table; a ratchet-wheel 79 carried by the sleeve; and an oscillating pawl-carrier 81 swiveled about the sleeve, all substantially as shown.

3. In combination with stem or spindle 64, sleeve 72 encircling the same and having disk 76 provided with notches 77; ratchet-wheel 79 also carried by said sleeve; pawl-carrier 81 having dog or pawl 82 and cam 89; spring 100 bolt or detent 78 adapted to enter the notches 77; and bar 91 connected with said spring-bolt and provided with stud or roller 90; the parts being arranged substantially as described, whereby the notched disk and consequently the sleeve and ratchet are normally held against rotation but are freed as the pawl-carrier completes its backward stroke preparatory to rotating the sleeve.

4. In combination with bed or table 61, stem or spindle 64 passing vertically through the same; sleeve 72 encircling the spindle and splined thereto; blocks 74 supported upon the table 61; rollers 73 carried by said blocks and extending into a circumferential groove 115 of the sleeve; and means for rotating said sleeve, all substantially as set forth.

5. In combination with spindle 64 and its sleeve 72 provided with notched disk 76; tubular casing 86; bolt or detent 78 mounted within said casing; spring 85 encircling said bolt; thimble 87 encircling the rear end of the bolt; and adjusting-screw 88 bearing against the rear end of the thimble and serving to regulate the compression of the spring.

6. In combination with spindle 64, sleeve 72 encircling said spindle and provided with ratchet-wheel 79; pawl-carrier 81 loosely en-

circling said sleeve; and nut 92 screwed upon said sleeve below the pawl-carrier, substantially as shown.

7. In combination with sleeve 72 provided with notched disk 76 and ratchet-wheel 79; pawl-carrier 81 provided with dog or pawl 82 and cam 89; and a detent adapted to engage the notched disk and having a stud or projection in the path of the cam 89, whereby the detent may be retracted on the back stroke of the pawl-carrier.

8. In combination with a bed or table, a form 115 movable over said bed and provided with ribs or flanges 137; and bars 138 applied to the bed and having overhanging lips or flanges to engage the ribs 137, whereby the form is held with its lower end close to the bed or table.

9. In combination with bed 61 having raised ribs or rails 139 and flanged bars 138; form 115 provided with rollers 121 and with ribs or projections 137.

10. In combination with bed 61, form 115 provided with ribs or projections 137; flanged arms 176 adapted to engage said ribs; and an ejector 163 movable longitudinally into or through the form, substantially as and for the purpose described.

11. In combination with bed 61 and an endless chain of forms movable across said bed, a sprocket-wheel 122 for giving motion to said chain; a shaft 128 carrying said sprocket-wheel; a notched disk 172 secured upon said shaft; a dog or detent to engage said disk and hold the shaft against accidental rotation; and a cam adapted to period-

ically withdraw the detent from engagement with the disk and permit rotation of the shaft and movement of the chain.

12. In combination with shape - carrier 40 head 65 and shapes 66; head or bunter 140 provided with stem 141; lever 142 connected with said stem; lever 144 connected with lever 142 by a link 143; reciprocating rod 132; and finger or arm 145, carried by the rod 132 45 and adapted to engage the lever 144, as and for the purpose set forth.

13. In combination with spindle 64 provided with a longitudinal slot or groove, encircling sleeve 72 provided with a feather or tongue to enter said groove and with a circumferential groove; blocks 74 provided with studs or arms 73 to enter the circumferential groove of the sleeve; a ratchet-wheel carried by the sleeve; a pawl-carrier; a pawl mounted upon said carrier and adapted to engage with the teeth of the ratchet-wheel; and means substantially such as described for raising and lowering the spindle 64.

14. In combination with the tray 337 and 60 temporary tray or receiving-board 349; the rake 360 adapted to engage the uppermost row of packages and to be drawn forward with the tray 337, thereby sweeping the contents from the temporary tray or receiver 65 into the tray 337.

In witness whereof I hereunto set my hand in the presence of two witnesses.

RUFUS L. PATTERSON.
